CLAIM

I claim the ornamental design for a socket, as shown and described.

DESCRIPTION

FIG. 1 is a front perspective view of a socket in accordance with the present design;

FIG. 2 is a rear perspective view of the socket of FIG. 1; FIG. 3 is a front side plan view of the socket of FIG. 1; FIG. 4 is a rear side plan view of the socket of FIG. 1; FIG. 5 is a right side plan view of the socket of FIG. 1; FIG. 6 is a left side plan view of the socket of FIG. 1; FIG. 7 is a top plan view of the socket of FIG. 1; and, FIG. 8 is a bottom plan view of the socket of FIG. 1.

Directional terms (such as top, bottom, etc.) are made with regard to the socket as shown and positioned in the drawings and are not intended to limit the scope of the invention.

(Continued)

The broken lines shown in the drawings are for the purposes of illustrating portions of the article that form no part of the claimed design.
